Ralph W. Wilson,

Inventor,

By his Attorneys, Dodeon & Roe.

UNITED STATES PATENT OFFICE.

RALPH WM. WILSON, OF NEW YORK, N. Y., ASSIGNOR TO THEODORE W. FOSTER & BRO. CO., OF PROVIDENCE, RHODE ISLAND, A CORPORATION OF MAINE.

POWDER AND ROUGE CONTAINER.

Application filed September 22, 1922. Serial No. 539,858.

To all whom it may concern:

Be it known that I, RALPH W. WILSON, a citizen of the United States, residing at New York, in the county of New York and State of New York, have invented a new and useful Improvement in Powder and Rouge Containers, of which the following is a specification.

My invention relates to that class of vanity boxes which are designed to contain both powder and rouge, it being well known that a very much larger quantity of powder is used than rouge. It is therefore most desirable to provide these in different sizes. Another very desirable and much sought after feature in cases of this kind is compactness.

My invention has for its object to provide a container or vanity box which will fulfill all of the foregoing objects and has for its further object to produce a vanity case which will be very thin and consequently easily carried.

My means of accomplishing the foregoing may be more readily understood by having reference to the accompanying drawings in which:

Fig. 1 is a view of my improved vanity case having the cover open.

Fig. 2 is a side elevation of the same.

Fig. 3 is a vertical sectional view;

Fig. 4 is a view of the bottom of the rotating bottom of the container.

Fig. 5 is a bottom view of the container with the cover shown in Fig. 4 removed.

Fig. 6 is a bottom view of the container with the rouge compartment closed.

Similar reference numerals refer to similar parts throughout the entire description.

As shown in the drawings, my vanity box comprises a powder container 10 in which is mounted a powder compact 11 of the standard form in which the powder is a compact rather than in the loose form. The container 10 is closed by a cover 12 which may be secured to the container by means of a hinge 13 or in any other suitable or convenient manner.

A mirror 14 is mounted inside of the cover 12 and a powder puff 15 is conveniently mounted intermediate the mirror and the top of the powder compact 11.

In the lower face of the powder compact 11 is formed a circular recess 16 in which is mounted a rouge compact 17. A separate powder or rouge puff 18 of suitable size to be located in the rouge container recess 16 is provided.

The container 10 has a double bottom, the outer wall 19 of which is revolvable upon the container 10 and is provided with an aperture 20 adapted to register with the recess 16 in which the rouge compact is mounted.

By rotating this outer bottom 19, it is apparent that the aperture 20 will be brought into register with the recess 16 thus making available the powder puff 18 and giving access to the rouge compact 17 mounted in the said recess. By mounting the rouge in the powder compact, it is apparent that I am able to materially lessen the thickness of the vanity case and the container, which is a result greatly to be desired in devices of this character.

Having described my invention what I regard as new and desire to secure by Letters Patent is:

1. A powder container, a cover therefor, a mirror in said cover, a powder puff in said container, a powder compact in said container, having a circular recess therein formed in the bottom thereof, a rouge compact mounted in said recess, there being an aperture in the bottom of the container, a double bottom for said container, the outer one being revolvably mounted and having an aperture therein adapted to register with the rouge containing recess.

2. A powder container, a cover therefor, a mirror in said cover, a powder puff in said container, a powder compact in said container, a rouge compact mounted in the bottom of said powder compact, a revolvable cover for said rouge compact.

3. A powder container, a cover therefor, a mirror in said cover, a powder puff in said container, a powder compact in said container, a rouge compact mounted in the bottom of said powder compact, a revolvable cover for said rouge compact, said cover being the outer portion of a double bottom.

In testimony whereof I have signed the foregoing specification.

RALPH WM. WILSON.
